UNITED STATES PATENT OFFICE.

WILLIAM MANDEL, OF MINNEAPOLIS, MINNESOTA.

WINDOW-SASH HOLDER.

1,381,422.

Specification of Letters Patent. Patented June 14, 1921.

Application filed August 21, 1920. Serial No. 405,007.

To all whom it may concern:

Be it known that I, WILLIAM MANDEL, a citizen of the United States, residing at Minneapolis, in the county of Hennepin and State of Minnesota, have invented certain new and useful Improvements in Window-Sash Holders, of which the following is a specification.

My invention relates to window sash holders and an object is to provide a spring-controlled device which is associated with the window frame and sash so that the latter will be held at any desired height without danger of falling. Another object is to provide means for locking the window at any desired height, such means being operable from within the room only.

The full objects and advantages of my invention will appear in connection with the detailed description thereof and the novel features embodied in my inventive idea will be particularly pointed out in the claim.

In the accompanying drawings, which illustrate the application of my invention in one form,—

Figure 1 is a view in vertical section taken on the line 1—1 of Fig. 3. Fig. 2 is a view in vertical section taken on the line 2—2 of Fig. 1. Fig. 3 is a view in horizontal section taken on the line 3—3 of Fig. 1. Fig. 4 is a view in vertical section taken on the line 4—4 of Fig. 3. Fig. 5 is an inside elevational view of a window sash and frame having my invention applied thereto. Fig. 6 is a view in horizontal section on the line 6 of Fig. 1. Fig. 7 is a fragmentary plan view of a perforated metal strip. Fig. 8 is an elevational view of the device.

The drawings illustrate a window embodying a lower sash 10, an upper sash 12 and a window frame 14, the latter being mounted in the walls of a building which include strips of lath 13 and plaster 15. Extending along the side of the window sash is a perforated metal strip 16 secured thereto at top and bottom by screws 18 as shown in Fig. 1. One of these strips is preferably secured to both sides of the lower and also of the upper sash. A roller 20 having teeth 22 for engaging the perforations in the strip 16 is supported in the window frame by means of a housing consisting of side members 24 and 26 secured together by screws 28, the housing being secured to the window frame by screws 30 passing through holes 32 in the housing. The member 24 is pro-

vided with an inwardly-extending shaft 34 upon which the roller 20 is rotatably mounted by means of an annular flange 36. A coiled spring 38 has its inner end secured to the shaft 34 and its outer end secured to the roller 20. The housing is provided with two pairs of forwardly-extending ears 40 and 42 between which extend, respectively, the pins 44 and 46. Rollers 48 and 50 are mounted on these pins, the window sash being provided with a slot 52 to permit the sash to move up and down. These rollers serve to hold the perforated strip 16 in engagement with the teeth 22 of the roller 20. In order to lock the window sash in any desired position I mount a rod 54 rotatably in the housing and to this rod is secured a metal plate 56 having perforations adapted to receive two or more of the teeth 22. The rod 54 extends through the frame 14 and has a handle portion 58 by means of which the rod may be rocked so as to cause the plate 56 to engage with the teeth 22 as shown in full lines in Fig. 1, or to cause said plate to be turned upwardly as shown in dotted lines in this figure. It will be understood that a complete window will preferably be provided with four of the devices just described, two at each side of the lower sash and two at each side of the upper sash.

The operation and advantages of my invention will be obvious from the foregoing description. The raising of a lower sash will cause spring 38 to be unwound and lowering of a lower sash will cause this spring to be wound up. The stiffness of the two springs preferably employed with each sash is sufficient to counterbalance the weight of the sash but not sufficient to cause the sash to move upwardly. It will be understood, of course, that the device is arranged to operate in reverse direction in connection with the upper sash. When a sash is being raised or lowered the locking plate 56 is moved into its inoperative or dotted-line position, as shown in Fig. 1, and upon lowering this plate the toothed roller is prevented from rotating, and since the strip 16 is firmly engaged by the teeth on the roller the window will be securely locked in any adjustable position and cannot be operated from the outside.

I claim:

A window sash holder comprising a perforated flexible metal strip adapted to be fastened to the side of a window sash, a hous-

ing adapted to be mounted in the window frame adjacent the sash, a fixed axle within said housing, a roller having an annular flange rotatably supported on said axle, a 5 coiled spring secured at its inner end to said axle and secured at its outer end to said roller, teeth on said roller adapted to engage in the perforations of said strip, ears on said housing, rollers supported by said ears ar-

ranged to hold said strip in engagement with 10 said teeth, a rod rotatably mounted in said housing, a perforated plate secured to said rod, and a handle on said rod whereby said plate may be caused to engage or disengage said teeth at will. 15

In testimony whereof I hereunto affix my signature.

WILLIAM MANDEL.
